(57) **CLAIM**

The ornamental design for a multi-position cylinder, as shown and described.

DESCRIPTION

FIG. 1 is a front, top, and right side perspective view of a multi-position cylinder;

FIG. 2 is a rear, bottom, and left side perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a left side elevational view thereof; and,

FIG. 8 is a right side elevational view thereof.

The cover on the top of the cylinder body is semitransparent and the objects within the cover form no part of the claimed design.

The broken lines in the drawings are included for the purpose of illustrating portions of the multi-position cylinder that form no part of the claimed design.
